UNITED STATES PATENT OFFICE.

JULIUS GRABER, OF NEW YORK, N. Y., ASSIGNOR TO GRABER CALCULATING MACHINE CO., A CORPORATION OF NEW YORK.

CALCULATING-MACHINE.

1,096,238.

Specification of Letters Patent. Patented May 12, 1914.

Application filed October 21, 1911. Serial No. 655,954.

To all whom it may concern:

Be it known that I, JULIUS GRABER, a citizen of the United States, residing at New York city, county and State of New York, have invented a new and Improved Calculating-Machine, of which the following is a specification.

This invention relates to a calculating machine of novel construction which is adapted to automatically perform addition, subtraction, multiplication and division.

The invention resides more particularly in a novel construction of a plurality of keys and key-actuated means for operating the ciphering device proper, illustrated and described in Patent No. 972,360 granted to me on October 11th, 1910.

In the accompanying drawing: Figure 1 is a plan of a calculating machine, embodying my invention; Fig. 2 an enlarged plan with the cover partly broken away; Fig. 3 a vertical cross section on line 3—3, Fig. 1; Fig. 4 a vertical longitudinal section on line 4—4, Fig. 3; Fig. 5 a vertical section on line 5—5, Fig. 2; Fig. 6 a sectional rear view of Fig. 5; Fig. 7 an enlarged vertical section on line 7—7, Fig. 5; Fig. 8 a vertical section on line 8—8, Fig. 1, and Fig. 9 a cross section on line 9—9, Fig. 8.

The ciphering mechanism contained in box 10 is actuated by a suitable number of keys 11 which are vertically reciprocable in the cover 12 of said box. The keys are arranged in parallel rows, each row containing nine keys, six of such rows being shown in the drawings. The finger pieces 13 of the keys of each row are labeled one to nine, the keys marked "1" being located in proximity to the front of the apparatus as illustrated in Fig. 1 of the drawings.

The keys of each row are adapted to actuate a shaft 14 located within box 10 below said row, which shaft may in turn be coupled to either one of a number of registering wheels 15 mounted on a carriage 16 which is arranged back of top plate 12. The ciphering mechanism referred to is more fully described in the above mentioned Patent #972,360 from which it appears that carriage 16 may be dispensed with and that the registering device suspended therefrom be accommodated within box 10 when the machine is to be used for addition and sub-

traction only, while the carriage is indispensable for multiplication and division. 55

The mechanism for transmitting motion from the keys to shaft 14 is as follows: To the lower end of each vertical key-shank is pivoted at 17 one arm of a two-arm lever 18 fulcrumed at 19 to a notched plate 20 which depends from cover 12, one plate 20 being provided for each row of keys "1" to "9". The other arm of lever 18 carries a pin 21 which is received within a corresponding slot formed in the shank 22 of a T-shaped 65 lever 22, 23, 24 fulcrumed to plate 20 as at 25 (Fig. 6). Arm 23 is provided with a knob 26 while arm 24 is influenced by a spring 27 which tends to lower shank 22 and thereby raise the key 11 connected thereto. Knob 26 is received within the groove 28 of a collar 29 axially slidable on shaft 14 which is squared so as to prevent an independent rotation of the collars 29 on their shaft. To each collar 29 is firmly secured a 75 toothed sector or motion transmitting member 30, which is adapted to engage a toothed wheel 31 provided with ten teeth and fast on a shaft 32 mounted in casing 10 in parallelism with shaft 14. The several sectors 30 80 are provided with different numbers of teeth according to the keys with which they are coöperable. The sectors of the "1" keys have but one tooth, the sectors of the "2" keys have two teeth, etc., the sector of the "9" keys having nine teeth. Shafts 14 are provided with miter wheels 33 meshing into similar wheels 34 of a common shaft 35 firmly mounted in suitable bearings of the front plate 36 of casing 10, wheels 34 partly 90 entering the latter through openings 37 of said plate. Shaft 35 is by miter wheels 38 connected to a vertical shaft 39 carrying a handle or crank 40. Means should further be provided for temporarily maintaining 95 the keys in their depressed position in order to likewise maintain the coöperating sectors 30 in the position to which they have been set by said keys, while handle 40 is operated for a purpose hereinafter described. These 100 means are shown to consist of a swinging bar or detent 41 fulcrumed to the lower side of cover 12 as at 42 and arranged in close proximity to each row of keys (Figs. 3, 4, 5 and 7). Each bar is influenced by a spring 105 43 that tends to draw its lower edge toward

its coöperating row of keys, the latter being provided with noses or abutments 44 adapted to be engaged by such edge. It is apparent from Fig. 7, that upon the depression of any key, its nose 44 will swing bar 41 away from the key, until in the lowermost position of the latter, the nose clears the plate and spring 43 is free to return the bar to its original position. In this way the manually depressed keys are automatically locked against rising and remain locked until the addition, etc., has taken place by giving handle 40 one complete turn as hereinafter more fully described.

At the end of each revolution of the handle, all depressed keys are automatically released in the following manner: At the inner side of front plate 36 is arranged a slide 45, held in position by a series of arms 46 depending from cover 12 and carrying pins 47 that engage corresponding slots 48 of said slide. The latter is normally retracted by a spring 49 while it is automatically advanced during the last stage of each rotation of handle 40 by means of a two-arm lever 50 pivoted to front plate 36 at 51. The upper arm of this lever is provided with a slot 52 accommodating a stud 53 of slide 45. The lower arm of lever 50 carries a pin 54 which is adapted to be engaged by the nose 55 of a cam disk 56 slidably mounted on a squared shaft 57. To disk 56 is firmly attached a collar 58, the groove 59 of which receives the lower arm of a T-shaped lever 60 pivoted at 61. The shank of lever 60 is connected to a two arm lever 62, to which in turn a key 63 having finger piece 64 is pivoted, the levers 60, 62 being equal in all respects to lever 22, 23, 24, and lever 18 respectively. Key 63 is provided with a nose 65 that is adapted to engage the lower side of cover 12 for purposes hereinafter described. In order to transmit the movement of slide 45 to bars 41, the slide is provided with a plurality of abutments 66 that are adapted to engage lugs 45 of said bars as appears in Fig. 4. As will be seen from this figure, the left hand abutment 66 bears against its bar 41, while a gap of gradually increasing width is formed between the coöperating abutments and bars from the left toward the right, so as to effect not a simultaneous but a consecutive engagement of the abutments with their bars. In this way power for advancing slide 45 is economized, while by the successive release of the depressed keys, shocks are obviated and objectionable noise prevented, as will be readily understood.

As thus far described, addition is performed by depressing the various keys 11 constituting the digits of the first number to be added. The depressed keys after being released by the fingers of the operator remain in their lowered position, as above described, the noses 44 first swinging bars 41

outward and then permitting the latter to fall in on top of said noses. During the descent of each key, its coöperating lever 18 and lever 22, 23, 24 have been tilted against the action of spring 27 (Figs. 5 and 6). In this way, the corresponding collar 29 and sector 30 have been axially shifted on shaft 14, so that said sector has become alined with its wheel 31 (left portion of Fig. 5). After the proper keys have been depressed, crank 40 is given one complete turn, so as to cause all shafts 14 and sectors 30 to simultaneously make one complete rotation. During this movement, the sectors pertaining to the depressed keys will cause their toothed wheels 31 to perform partial rotations according to the teeth-number of said sectors, while the sectors pertaining to the raised keys will turn idle, as they are out of mesh with their wheels 31 (right part of Fig. 5). Thus for instance, if in any one vertical key-row, the key "4" is depressed, its sector 30, having four teeth, will rotate the coöperating wheel 31 and shaft 32 through an angle corresponding to four tenths of a revolution. As will be seen from Fig. 7, the rotation of shafts 32 will be completed during the first portion of the rotation of crank 40, the remaining portion of such rotation being utilized for operating bars 41 in order to release the depressed keys. Thus after the rotation of shafts 32 has been completed, the nose 55 of cam 56 which participates in the rotation of shafts 14 comes into engagement with pin 54 of lever 50, thereby tilting the latter and shifting slide 45 toward the left (Fig. 4). In this way the bars 41 are swung away from their respective key-rows, thereby liberating noses 44 and permitting springs 43 to raise the previously depressed keys 11. While the rotation of crank 40 is being completed, pin 54 will gradually return to its normal position owing to the retraction of slide 45 through spring 49.

The means by which the partial rotations of shafts 32 are transmitted to registering wheels 15 is fully described in my above cited patent, the shafts 32 of this application corresponding to the shafts 41 of said patent. It may be stated however that upon each shaft 32 is slidably mounted a sleeve 67, carrying at its ends, beveled gear wheels 68, 69, either one of which is adapted to engage a similar wheel 70. The latter is keyed to the spindle 71 of dial 15, the uppermost number of which is displayed through a window 72 of carriage 16, the latter being rotatable and longitudinally movable on a spindle 73 of casing 10. A sliding bar 74 straddled by the hubs of wheels 68, 69 is actuated by a hand lever 75 through a suitable link and lever connection 76, so as to either adapt the machine for addition and multiplication, or for subtraction and division. Each shaft 32 is further provided

with a toothed wheel 77, a retaining spring 78, a disk 79 having concave teeth, and a mutilated barrel 80, the parts 79, 80 constituting means for locking dials 15 in position, while being inoperative, all as described in my above cited patent. Additional means are provided for carrying tens, hundreds, etc., during the calculating operation, said means being also fully disclosed in my patent and comprising a tappet 81 mounted on each spindle 71 and adapted to oscillate a shifting lever 82. The latter in turn engages a grooved collar 83 which is integral with barrel 80 and has a finger 84 which may be brought into mesh with toothed wheel 77 upon a tilting of lever 82, so as to advance said wheel for one tooth and thereby rotate the neighboring dial 15 for one digit.

If a multiplication is to be performed instead of an addition as above described, the depressed keys should remain in their lowered state after a rotation of crank 40 has been completed. For this purpose key 63 is depressed while pushing the same slightly backward, so that its nose 65 engages the lower side of cover 12, in which position the parts are maintained by frictional contact. By this depression of key 63, cam 56 is shifted toward the right (Fig. 8) to bring it out of engagement with pin 54. In this way slide 45 will remain at rest irrespective of the number of turns imparted to crank 40, so that the depressed keys are locked against rising. In order to raise the keys after the multiplication has been performed, an additional key 85 is arranged in proximity to key 63. Key 85 is slotted at 86 for the accommodation of a screw 87 tapped into a depending bracket 88 and insuring a true vertical play of the key. The latter is provided at its lower end with a beveled projection 89 that is adapted to engage pin 54 of lever 50. By depressing key 85, projection 89 will by engaging pin 54, tilt lever 50, so as to oscillate bars 41 and release the depressed keys, while upon the release of key 85, a spring 90 returns the latter into its raised position.

I claim:

1. In a calculating machine, a depressible key, a motion transmitting device controlled thereby, a ciphering device adapted to coöperate with said motion-transmitting device upon a depression of the key, means for retaining said key in its depressed position, and means for actuating the motion-transmitting device and for subsequently releasing the key-retaining means.
2. In a calculating machine, a spring-influenced depressible key, a rotary motion transmitting device controlled thereby, a ciphering device adapted to coöperate with said motion-transmitting device upon a depression of the key, means for retaining said

key in its depressed position, and means for rotating the motion-transmitting device and for subsequently releasing the key-retaining means.

3. In a calculating machine, a spring-influenced depressible key, a toothed sector controlled thereby, a toothed wheel adapted to be engaged by the sector upon a depression of the key, means for retaining said key in its depressed position, a ciphering device operated by said toothed wheel, and means for rotating the sector and for subsequently releasing the key retaining means.

4. In a calculating machine, a depressible key, a toothed wheel, a ciphering device operatively connected thereto, a slidable and rotatable sector which is normally out of alinement with the toothed wheel, means actuated upon a depression of the key for sliding the sector into alinement with said wheel, means for retaining the key in its depressed position, and means for rotating the sector and for subsequently releasing the key.

5. In a calculating machine, a depressible key, a toothed wheel, a ciphering device operatively connected thereto, a slidable and rotatable sector which is normally out of alinement with the toothed wheel, a spring-influenced lever system actuated by the key and adapted to slide said sector into alinement with the wheel, means for retaining the key in its depressed position, and means for rotating the sector and for subsequently releasing the key.

6. In a calculating machine, a spring-influenced depressible key, a toothed sector controlled thereby, a toothed wheel adapted to be engaged by the sector upon a depression of the key, means for retaining said key in its depressed position, a ciphering device operated by said toothed wheel, and a manually operable crank for rotating the sector and subsequently releasing the key.

7. In a calculating machine, a depressible key, a slidable and rotatable sector controlled thereby, a toothed wheel adapted to be engaged by said sector, a ciphering device operable by the toothed wheel, and means for retaining the sector in operative relation to said wheel.

8. In a calculating machine, a shaft, a sector slidably and non-rotatably mounted thereon, a toothed wheel which is normally out of mesh with the sector, a ciphering device operable by the toothed wheel, a depressible key adapted to slide the sector into mesh with said toothed wheel, and a crank operatively connected to the shaft.

9. In a calculating machine, a squared shaft, a sector loosely mounted thereon, a toothed wheel adapted to be engaged by the sector, a depressible key, a spring-influenced lever system operable by the key for axially moving the sector on the shaft, means for

- retaining the key in its depressed position, and means for rotating the shaft.
10. In a calculating machine, a shaft, a grooved collar slidably and non-rotatably mounted thereon, a toothed sector on said collar, a toothed wheel adapted to be engaged by the sector, a ciphering device operable by said wheel, a depressible key, a spring-influenced lever actuated by the key and engaging the collar-groove, means for retaining the key in its depressed position, and means for rotating the shaft.
11. In a calculating machine, a ciphering device, a depressible key, a crank, a motion-transmitting device operable by said crank and adapted to actuate the ciphering device upon a depression of the key, and an oscillating detent adapted to lock the key in its depressed position.
- 20 12. In a calculating machine, a ciphering device, a depressible key, a crank, a motion-transmitting device operable by said crank and adapted to actuate the ciphering device upon a depression of the key, an oscillating detent adapted to lock the key in its depressed position, and a crank adapted to actuate the motion transmitting device and subsequently operate the detent for unlocking the key.
- 30 13. In a calculating machine, a ciphering device, a depressible key, a crank, a motion-transmitting device operable by said crank and adapted to actuate the ciphering device upon a depression of the key, an abutment on the key, and an oscillating detent adapted to engage said abutment.
- 40 14. In a calculating machine, a depressible key, an abutment thereon, a two-arm lever pivoted to the key, a T-shaped spring-influenced lever pivoted to the two arm lever, a shaft, a collar slidably thereon and engaged by the T-shaped lever, a toothed sector on said collar, a ciphering device adapted to be actuated by said sector, and an oscillating detent adapted to engage the abutment.
- 50 15. In a calculating machine, a plurality of depressible keys, motion transmitting devices controlled thereby, ciphering devices adapted to coöperate with said motion transmitting devices, swinging bars for retaining the keys in their depressed position, and means for consecutively actuating the motion transmitting devices and for the swinging bars.
- 60 16. In a calculating machine, a plurality of rows of depressible keys, motion transmitting devices controlled thereby, ciphering devices adapted to coöperate with the motion transmitting devices of the respective key-rows, swinging detents adapted to maintain the keys in their depressed position, and means for tilting said detents to thereby release the keys.
- 65 17. In a calculating machine, a plurality of rows of depressible keys, motion-transmitting devices controlled thereby, ciphering mechanism adapted to be actuated by said motion transmitting devices, oscillating detents adapted to maintain the keys in their depressed position, one detent being provided for each key-row, a slide having a plurality of projections that are adapted to consecutively engage the detents, and means for actuating said slide.
- 70 18. In a calculating machine, a plurality of rows of depressible keys, motion-transmitting devices controlled thereby, ciphering mechanism adapted to be actuated by said motion transmitting devices, oscillating detents adapted to maintain the keys in their depressed position, one detent being provided for each key-row, a slide adapted to consecutively engage the detents, and means for actuating the motion transmitting devices and for subsequently moving the slide.
- 80 19. In a calculating machine, a plurality of rows of depressible keys, motion-transmitting devices controlled thereby, ciphering mechanism adapted to be actuated by said motion transmitting devices, oscillating detents adapted to maintain the keys in their depressed position, one detent being provided for each key-row, a slide adapted to consecutively engage the detents, and a manually operable crank for actuating the motion transmitting devices and for subsequently moving the slide.
- 90 20. In a calculating machine, a plurality of rows of depressible keys, motion-transmitting devices controlled thereby, ciphering mechanism adapted to be actuated by said motion transmitting devices, oscillating detents adapted to maintain the keys in their depressed position, one detent being provided for each key-row, and means for consecutively withdrawing said detents from their respective key-rows.
- 100 21. In a calculating machine, a plurality of keys, abutments on said keys, motion-transmitting devices controlled by the keys, ciphering mechanism adapted to be actuated by said motion transmitting devices, a plurality of oscillating detents adapted to engage the abutments, a spring-influenced slide adapted to engage the detents, a cam and an additional key, both of which last named elements are adapted to actuate the slide.
- 105 22. In a calculating machine, a plurality of keys, abutments on said keys, a plurality of oscillating detents adapted to engage said abutments, a slide adapted to engage the detents, a lever pivotally connected to the slide, a pin projecting from said lever, a cam adapted to engage said pin, and means for rotating said cam.
- 110 23. In a calculating machine, a plurality of keys, abutments on said keys, a plurality of oscillating detents adapted to engage said

- abutments, a slide adapted to engage the detents, a lever pivotally connected to the slide, a pin projecting from said lever, a cam adapted to engage said pin, and an additional key also adapted to engage said pin. 15
24. In a calculating machine, a plurality of keys, a plurality of detents adapted to maintain the keys in their depressed position, a slide adapted to engage said detents, means for actuating said slide, an additional key, and means controlled thereby for disconnecting the slide from said actuating means. 10
25. In a calculating machine, a plurality of keys, a plurality of detents adapted to maintain the keys in their depressed position, a slide adapted to engage said detents, a cam adapted to actuate the slide, means for rotating said cam, an additional key, and means controlled thereby for disconnecting the cam from the slide. 20
26. In a calculating machine, a plurality of keys, a plurality of detents adapted to maintain the keys in their depressed position, a slide adapted to engage said detents, a lever pivotally connected to said slide, a pin on said lever, a shaft, a cam slidable thereon and adapted to engage the pin, and an additional key adapted to shift the cam on the shaft away from the pin. 25
27. In a calculating machine, a plurality of keys, a plurality of detents adapted to maintain the keys in their depressed position, a slide adapted to engage said detents, a pin for advancing said slide, a cam adapted to engage said pin, a first additional key 30
- adapted to advance the pin, and a second additional key for bringing the cam out of engagement with the pin. 40
28. In a calculating machine, a plurality of keys, a plurality of detents adapted to maintain the keys in their depressed position, a slide adapted to engage said detents, a first lever pivotally connected to said slide, a pin on said lever, a shaft, means for rotating the same, a cam slidable on the shaft and adapted to engage the pin, a grooved collar on the cam, a second lever engaging the collar groove, and an additional key for actuating said second lever. 45
29. In a calculating machine, a plurality of keys, a plurality of detents adapted to maintain the keys in their depressed position, a slide adapted to engage said detents, a lever pivotally connected to said slide, a pin on said lever, and an additional key having a beveled abutment that is adapted to engage said pin. 50
30. In a calculating machine, a plurality of depressible keys, motion transmitting devices controlled thereby, ciphering devices adapted to coöperate with said motion transmitting devices, means for retaining the keys in their depressed position, means for actuating the motion-transmitting devices and for subsequently releasing the keys, and means for rendering said releasing means inoperative. 55
